UNITED STATES PATENT OFFICE.

JOHN C. DODSON, OF STONE MOUNTAIN, GEORGIA.

STONE-DRESSER.

1,240,687.

Specification of Letters Patent. Patented Sept. 18, 1917.

Application filed September 27, 1916. Serial No. 122,463.

To all whom it may concern:

Be it known that I, JOHN C. DODSON, a citizen of the United States, residing at Stone Mountain, in the county of Dekab 5 and State of Georgia, have invented certain new and useful Improvements in Stone-Dressers, of which the following is a specification.

This invention has relation to an attachment for a jeweler's lathe for grinding pivots, arbors, etc., and the nature and objects thereof will be readily apparent to those skilled in the art to which it appertains, in the light of the following explanation of the accompanying drawings, illustrating what I now believe to be the preferred embodiment, or mechanical expression of my invention, from among other forms and arrangements within the spirit 20 thereof, or the scope of the appended claims.

However, an object of the invention is to provide a device adapted to be attached to a jeweler's lathe, and embodying mechanism for imparting a reciprocatory movement to a grinding stone whereby, a pivot to be ground may be held in the head stock of the lathe, and engaged upon the abrasive element to form a conical pivot point or a 30 shoulder pivotal point, by varying the degree of inclination of the abrasive element by means provided for that purpose.

In addition to the foregoing my invention comprehends improvements in the details of 35 construction, and arrangement of parts to be hereinafter more fully described, and particularly set forth in the appended claims.

In the accompanying drawings in which 40 similar and corresponding parts are designated by the same characters of reference throughout the several views in which they appear:

Figure 1, is a transverse sectional view 45 taken through a jeweler's lathe, and illustrating the application thereto of my invention.

Fig. 2, is a view in plan of the lathe, and my device attached thereto.

Fig. 3, is a view on an enlarged scale, illustrating my device in longitudinal section, and

Fig. 4, is a transverse sectional view taken on the line 4—4 of Fig. 1.

With reference to the drawings, 1 indicates the bed of a jeweler's lathe having a

head stock and tail stock designated at 2 and 3 respectively, the head stock being provided with the usual pulleys 4 for rotating the chuck plate 5. In conjunction with the 60 jeweler's lathe there is provided a counter shaft 6 disposed parallel to the bed of the lathe and some distance therefrom, supported in bearing brackets 7, and having belt pulleys 8 and 9 fixedly secured thereto. 65 The belt pulley 9 is operated by means of a belt proceeding from a treadle (not shown), which may be located beneath the work bench upon which the lathe and the counter shaft are supported. Thus far the description is that of a jeweler's lathe outfit at present employed.

My invention is in the way of an attachment to be applied to the bed of the lathe, and comprises a frame plate 10 which is 70 rested upon the bed of the lathe and extended transversely thereacross and secured thereto by means of a bolt 11 which passes through apertures provided in said plate and the bed of the lathe. The frame plate 80 10 is provided at either end with a pair of transversely spaced studs 12 for supporting in parallelism a pair of longitudinally extending guide rods 13, disposed in superposed relation above the frame plate 10. 85 Nuts 14, applied to the upper threaded ends of the studs 12 serve to secure the ends of the guide rods to the studs to prevent disengagement thereof.

A slide 15 is provided, having recesses 90 16, at either end of the slide, and at opposite edges thereof, to receive therein the guide rods 13, whereby the slide is mounted for longitudinal movement in a direction transversely of the lathe bed. At one end of the 95 frame plate 10, a pair of upstanding transversely spaced bearing brackets 17 are mounted, for supporting a transversely extending crank shaft 18 having an offset portion 19 located in longitudinal alinement 100 with the slide 15, said offset portion being connected to said slide by means of a connecting rod 20. A pinion 21 is fixedly secured to said crank shaft, and is designed for meshing engagement with a smaller 105 pinion 22 mounted upon a transversely extending shaft 23, which is journaled at either end in upstanding bearing brackets 24, spaced transversely and supported at their lower ends upon a horizontal bracket arm 110 25 extending transversely of the device and having its inner end bent upward as at 26

and secured to the under side of the frame plate 10. A brace 27 may be provided for additional support to the arm 25 and to that end is connected at one end to said arm 5 and at the opposite end to the under side of the frame plate 10. The arm 25 and consequently the bracket it supports, is disposed parallel to the bed of the lathe and toward the head stock, and a pulley 28 is 10 secured to the shaft 23 for rotation therewith, and in transverse alinement with the pulley 4 of the lathe, and also in alinement with the pulley 8 of the counter shaft 6 so that a belt 29 may be passed around the 15 aforesaid pulleys 4 and 8 with its lower stretch resting upon the pulley 28, as illustrated to advantage in Fig. 2.

When the lathe is set in motion through the medium of the counter shaft after the 20 usual fashion, the belt 29 imparts to the pulley 28 a rotative motion which is transmitted from the shaft 23 through the medium of the pinions 21 and 22 to the crank shaft 18, the rotative motion thereof being 25 converted into reciprocatory movement of the slide 15 through the medium of the offset portion 19 and the connecting rod 20.

To proceed with a description of the supporting means for the abrasive element, 30 indicates a frame super-posed upon the slide 15 in parallelism thereto and in vertically spaced relation, and is formed at either end with upstanding portions 31 and 32. A hollow post 33 is erected centrally upon the 35 slide 15, and is adapted to enter an opening in the plate 30, the upper end of the post being threaded to receive a nut 34 which prevents vertical displacement of the plate 30. At either side of the post 33 a stud 35 40 is extended from the slide 15 for the purpose of entering sleeves 36 depending from the under side of the plate 30, and coil springs 37 are embraced about the stud 35 and bear at either end upon the upper surface of the 45 slide 15 with the lower end of the sleeve 36, thereby urging the plate 30 in an upward direction which movement is limited by engagement of the plate with the nut 34.

The end member 31 of the plate 30 is enlarged as at 38 and threaded to receive the adjusting screw 39 of the abrasive element. The inner end of the threaded rod 39 is bifurcated to form spaced extensions 40 which are secured at their terminals to a 55 distance member 41 having a polygonal opening formed centrally therein, and set screws 42 extend radially into said discous member, with their ends projecting into the aforesaid polygonal opening. The opposite 60 end of the threaded element 39 is formed into a wheel 43 whereby the said element may be rotated to effect the longitudinal adjustment of the stud. The abrasive element as indicated at 44 is in the form of a 65 relatively long bar, preferably triangular

in cross section, and adapted to be received at one end within the polygonal opening formed in the chuck plate 41. The opposite end of the abrasive element 44 is supported in a chuck member in the form of a cylindrical member 45 which is seated within an opening formed in the upstanding member 32 of the plate 30, a plug 46 being slidably mounted within the member 45 and having a polygonal opening 47 to receive the end 70 of the abrasive element. A spring 48 is disposed within the member 45 to urge the plug 46 in an outward direction.

To insert the abrasive element within the supporting members therefor, one end is engaged within the plug 46 and the plug moved inward against the tension of the spring 48 until the opposite end of the abrasive element is in position to be inserted in the polygonal openings of the chuck 85 plates 41. The spring 45 urges its plug 46 and consequently the abrasive element in a longitudinal direction, and when the end of the abrasive element is seated within the chuck plate 41 as aforesaid, the set screws 90 42 are rotated until engagement from the abrasive element to securely hold the same against displacement, is established.

In the operation of this invention, the pivot pin to be ground is inserted, as indicated in Fig. 2, in the chuck plate 5 of the lathe, the same being indicated at 49, and the end thereof to be ground is rested upon the surface of the abrasive element 44. If the end of the pivot pin is to be provided 95 with a shoulder, the upper surface of the abrasive element should be horizontal and the length of the pivot to be ground on the pin determined by adjusting the device as a whole longitudinally of the bed plate of 100 the lathe. When the chuck plate of the lathe is set in motion through the medium of the pulleys 4 in the manner hereinbefore set forth, a reciprocatory movement is imparted to the abrasive element, and this motion, in addition to the rotative motion of 105 the pivot pin 49, results in the formation of a shoulder pivot on the end thereof in contact with the abrasive element. During the reciprocation of the abrasive element spring 110 37 encircling the stud 35 exerts a slight upward pressure upon the abrasive element which retains the said element in engagement with the pivot pin throughout the length of the stroke. To provide a conical 115 pivot upon the end of the pivot pin, the abrasive element 44, may be rotated by means of the handle 43 so as to dispose its upper surface at an angle to the axis of the pivot pin, whereupon a conical point will 120 be ground during longitudinal reciprocation of the abrasive element.

While I have illustrated and described my invention with some degree of particularity, I realize that in practice various alterations 125 130

thereover may be made, and I therefore reserve the right and privilege of changing the form of the details of construction, or otherwise altering the arrangement of the correlated parts without departing from the spirit of the invention, or the scope of the appended claims.

Having thus described my invention, what I claim as new and desire to secure by Letters Patent is:—

1. The combination of a jeweler's lathe adapted to receive a pivot pin in its chuck, of a pivot grinding attachment including a frame plate adapted to be secured to the lathe bed for adjustment in a longitudinal direction, a slide mounted upon the frame plate for movement in a direction transverse of the lathe bed, a frame mounted upon the slide, resilient means for urging the frame in an upward direction, chuck members at opposite ends of the frame, an abrasive element supported at either end in the chuck members and adapted to engage the pivot pin to be ground, means for imparting a reciprocatory movement to the slide, and means for actuating said slide actuating means and the lathe chuck.

2. A pivot grinding attachment for jewelers' lathes including a frame plate, a slide mounted thereon for reciprocatory movement, a frame mounted on said slide, an abrasive element, means on one end of the frame for receiving one end of the abrasive element, a threaded member mounted in the opposite end of the frame for adjustment in a direction longitudinally of the frame and abrasive element, and means on said threaded element for engaging the other end of the abrasive element.

3. A pivot grinding attachment for jewelers' lathes including a frame plate, a slide mounted thereon for reciprocatory movement, a frame mounted on said slide, a chuck member mounted on one end of the frame including a member formed with a cylindrical recess, a cylindrical block mounted in said recess for rotative and sliding movement, an abrasive element having one end mounted in said block, a spring within the recess element bearing against the block

to urge the same in an outward direction, a chuck member on the other end of the frame including a threaded element mounted therein for adjustment in a direction longitudinally of the abrasive element, and a chuck member mounted on said threaded member for receiving the opposite end of the abrasive element.

4. A pivot grinding attachment for jewelers' lathes, including a frame plate, a slide mounted thereon for reciprocatory movement, a frame mounted on said slide, an abrasive element, means on one end of the frame for supporting one end of the abrasive element comprising a recessed member, a block mounted in said member for rotative and reciprocatory movement therein, a spring within the recessed member to urge the block outward, said block having a recess to receive one end of the abrasive element, a threaded member mounted in the opposite end of the frame for adjustment in a direction longitudinally of the abrasive element, one end of said threaded element being bifurcated, a disk member mounted within said bifurcated portion and having a recess to receive the opposite end of the abrasive element, and set screws in said disk member for securing the abrasive element against displacement.

5. A pivot grinding attachment for jewelers' lathes, including a frame plate, a slide mounted thereon for reciprocatory movement, a threaded stud mounted on said slide, a frame having a central opening to receive the stud, a nut applied to said stud to secure the frame against dislodgment, sleeves mounted on the under side of the frame at opposite sides of the stud, studs on the slide adapted to enter the said sleeves, coil springs encircling the studs for urging the frame upward, an abrasive element, and means on the slide for supporting said abrasive element.

In testimony whereof I affix my signature in presence of two witnesses.
